Inventor:

John Bradley,
By his Attorney,
Addison S. Diossy

UNITED STATES PATENT OFFICE.

JOHN BRADLEY, OF NEWARK, NEW JERSEY.

CAR-COUPING.

SPECIFICATION forming part of Letters Patent No. 257,817, dated May 9, 1882.

Application filed August 3, 1881. Renewed April 11, 1882. (No model.)

To all whom it may concern:

Be it known that I, JOHN BRADLEY, of the city of Newark, in the State of New Jersey, have invented a new and useful Improvement in Car-Couplings, of which the following is a specification.

My invention relates to that class of car-couplings in which a swinging link pivoted in the draw-head is employed to engage a projection or hook upon the draw-head of the end of the car adjacent; and its object is to render the operation of coupling more convenient and safer than heretofore.

It consists in the arrangement and combination, in a suitable draw-head, of a link formed with an eccentric and of a movable cam-block actuated by suitable rods or levers for the purpose of controlling the position of said link either from the top or sides of the car.

In the accompanying drawings, Figure 1 represents the adjacent ends of the two cars coupled together by my improved device, one side of the draw-head of each coupling being partially broken away to show the movable cam-blocks.

Fig. 2 is an isometrical perspective of one end of a car provided with my improved coupling. Fig. 3 is an isometrical perspective of the cam-block, and Fig. 4 a similar view of a link provided with the eccentric.

The draw-head A consists of a hollow neck or body, a , with a solid head or buffer-plate, a' , provided with a slot or opening, a^2 , in the face of the buffer-plate for a link, and a well-hole, a^3 , for a coupling-pin, a^4 , near and just back of the buffer-plate a' in the draw-head, for use when it is desired to couple with a car provided only with ordinary link-and-pin coupling. The draw-head proper and buffer-plate a' have upon the lower or under side a horn or projection, b , at the buffer end extending downward for the purpose of holding or retaining the coupling-frame C, which is thrown around the horn or projection b , which coupling-frame C locks or couples the two draw-heads together. This coupling-frame C has two movements—an upward movement and a downward movement—both in the arc of a circle and working outside of the lower or under side of the draw-head a' and buffer-plate, and is raised up and around the horn or projection b of both the draw-heads. This coupling-frame C may be made of any

shape, and forged, pressed, or cast from iron, steel, or other metal, and of one continuous piece of metal, so as to retain all the strength of such metal, and is welded together at its inner end to form an eccentric, e , said eccentric moving perpendicularly up and down or following the face of the cam. The coupling-frame C is operated from the top of the car, or from either or both sides of the car. The coupling frame or link C is raised into its position for coupling or connecting the opposite draw-head each to the other by an eccentric or cam block, D, which eccentric or cam is a part of or is attached to the lower end of the perpendicular or service rod d , and which cam D leans or rests directly upon the inner or smaller end, c , of the coupling frame or link. This cam D is moved within a recess or well-hole, e , made in the body of draw-head A, open at the lower or under side to allow the necessary motion for the cam D. The cam-block has two flaring holes or cores, $d' d'$, cast, formed, bored, or punched into it on opposite sides for the purpose of receiving the ends of the side rods, E E, which raise or lower the cam D in connection with the service or upright rod d . By depressing or bearing down the perpendicular or service rod d the cam D is depressed upon the inner or small end, c , of the coupling frame or link C, causing it to rise into its proper position for coupling with the opposite draw-head. This inner or small end, c , of the coupling-frame C is in the form of an eccentric bearing, e , which moves or travels upon the face of the cam D as it is depressed or raised to lock or unlock the connection between the two draw-heads. This cam D has two movements—an upward movement and a downward movement—operated by hand by the perpendicular or service rod d , and moving in a recess or well, e , made in the neck or body of the draw-head A, together with the inner or small eccentric end of the coupling-frame C, all operated from the roof of the freight-car, or from either or both sides of the car, at the end, and from the ground at the outside of the car. The cam D may be made triangular, convex, concave, flat, or square upon the face, as may be required. The coupling frame or link C may be made of any shape, circular, oblong, elliptic, or square, terminating in an eccentric, 55 60 65 70 75 80 85 90 95 100

c. The coupling-frame C hangs perfectly free, giving all the lateral motion that is required by the swaying of the cars.

The service or upright rod has two auxiliary or parallel rods, E E, extending from each side of the service or upright rods to the lower or under side of the cam D to the outer side, and at the end and underneath the end sill of the car, for the purpose of coupling or uncoupling the draw-head D from the ground. Thus I have complete control of the movements of the coupling-frame C from the top and at either end and at both sides of the car, and from the ground. These several parts may be made of cast or wrought iron, steel, or other metal.

What I claim, and desire to secure by Letters Patent, is—

1. In a car-coupling substantially such as de-

scribed, the pivoted upwardly-engaging link provided with the eccentric, in combination 20 with movable cam-block when operating in conjunction, substantially in the manner and for the purpose set forth.

2. In a car-coupling substantially such as described, the movable cam-block provided with 25 and capable of being actuated by either the vertical rod from the top of the car or the auxiliary side levers for the purpose of controlling the position of the upwardly-engaging link, substantially in the manner and for the purposes herein set forth.

JOHN BRADLEY.
